UNITED STATES PATENT OFFICE.

THOMAS J. GAFFNEY, OF NEWARK, NEW JERSEY.

DESIGN FOR AN EAR-PROTECTOR.

52,820.

Specification for Design. Patented Dec. 31, 1918.

Application filed May 23, 1918. Serial No. 236,235. Term of patent 3½ years.

To all whom it may concern:

Be it known that I, THOMAS J. GAFFNEY, a citizen of the United States of America, residing at Newark, in the county of Essex and State of New Jersey, have invented a new, original, and ornamental Design for an Ear-Protector, of which the following is a specification, reference being had to the accompanying drawing, forming part thereof, in which—

Figure 1 is a front elevation of an ear protector in which my invention is embodied in one form;

Fig. 2 is a plan thereof;

Fig. 3 is a rear elevation thereof.

The present invention relates to an ear protector of fabric. The front or forehead portion A, as shown, is narrower than the rear portion B, which is joined to the forehead portion by side portions C—C, which gradually narrow from the width of the back portion to the forehead portion A.

I claim:—

The new ornamental design for an ear protector, as shown.

THOMAS J. GAFFNEY.
